Inventor:

John M. Carroll.

By his Attorney.

Jas. F. Williamson,

UNITED STATES PATENT OFFICE.

JOHN M. CARROLL, OF GRAND FORKS, NORTH DAKOTA.

VERTICAL EXCAVATOR.

SPECIFICATION forming part of Letters Patent No. 574,660, dated January 5, 1897.

Application filed April 21, 1896. Serial No. 588,439. (No model.)

To all whom it may concern:

Be it known that I, JOHN M. CARROLL, a citizen of the United States, residing at Grand Forks, in the county of Grand Forks and State of North Dakota, have invented certain new and useful Improvements in Vertical Excavators; and I do hereby declare the following to be a full, clear, and exact description of the invention, such as will enable others skilled in the art to which it appertains to make and use the same.

My invention relates to excavators, and has for its object to provide an improved machine of this class.

The machine herein disclosed is provided with vertically-acting augers, and was especially designed for use in connection with that certain other excavating-machine described in my companion case filed of even date here-with, which is provided with a horizontally-acting auger. For purposes of distinction my present case is marked "A," and may be called the "vertical" excavator, and my companion case is marked "B," and may be called the "horizontal" excavator.

The vertical excavator herein disclosed was especially designed for making the vertical openings necessary for starting and operating the horizontal auger of my companion machine and for the introduction of the pipes which it is desired to lay in the horizontal trench. The present machine is, however, capable of general use for making trenches and many other kinds of excavations.

My invention consists of the novel devices and combinations of devices which will be hereinafter described, and defined in the claims.

The invention is illustrated in the accompanying drawings, wherein, like letters referring to like parts throughout the several views—

Figure 1 is a side elevation of the machine with some parts broken away. Fig. 2 is a rear elevation of the same. Fig. 3 is a plan view of the machine with some parts broken away. Fig. 4 is a view partly in section and partly in elevation, the section being on the line $x^4 x^4$ of Fig. 3. Fig. 5 is a detail, partly in longitudinal vertical section, lengthwise of the truck, showing the relation of one of the auger-stems to its feeding, guiding, and control-

ling devices with said parts as they would appear when the auger is free for its downward feed in the boring action. Fig. 6 is a detail of some of the parts shown in Fig. 5 with the same as they would appear when the auger is held by the friction-clamp or controlling device. Fig. 7 is a detail in plan view, showing the hub of the gear which works on the auger-stem; and Fig. 8 is a detail showing the end or a cross-section of the auger-stem.

a a' a^2 represent, respectively, the wheels, the axles, and the draft-tongue of an ordinary truck of the proper dimension to straddle the trench. a^3 and a^4 represent, respectively, the skeleton platform and the bunkers of a suitable truck-body, which is supported from the axles a' in the ordinary or any suitable way. The truck-body is represented as braced from the bunkers or the axles by suitable brace-rods a^5 .

From the side bars of the platform a^3 rise four posts b , set on slightly-convergent lines in respect to each other longitudinally of the truck and united at their upper ends by a rectangular open frame or skeleton cap b' . The side pairs of the said posts b are united below the cap b' by side pieces b^2 , and the said side pieces b^2 are connected crosswise of the truck by transoms or cross-bars b^3 . The posts b are also connected crosswise of the truck by tie-bars or transoms b^4 . The front and rear members of the cap b' are connected longitudinally of the truck by a pair of central tie-bars b^5 , which are spaced a short distance apart from each other on opposite sides of the center of the truck. The said posts b unite with the side rails a^3 by means of stepped joints b^6 and angle-iron joint-plates b^7 , bolted to the said posts and said rails, as best shown in Fig. 1. The said parts (marked with the letters b to b^7 , inclusive) constitute an upright skeleton frame of substantially pyramidal form, supported from the truck platform or body as its base, and which is adapted, in turn, to support the augers and the means for operating and controlling the same.

c represent the auger-blades, and c' c^2 the sectional stems of the same. The said stem-sections c' c^2 are provided with joint-flanges c^3 on their meeting ends, which are bolted together as a means of separably connecting

the auger-bodies with the upper sections c^2 of the stems. The said augers are vertically disposed side by side lengthwise of the truck in the median line of the same. The upper sections c^2 of the auger-stems work through vertical bearings c^4 , fixed to the transoms or cross-ties b^3 of the frame and through bearings c^5 at the ends of a yoke c^6 , which is disposed longitudinally of the truck, with its extremities resting on the hubs of spur-gears c^7 , mounted on the auger-stem c^2 and resting on the bearings c^4 . The said gears c^7 are provided with feathers c^8 in their hubs, which engage in longitudinal grooves c^9 , formed in the stems c^2 , which connection rotatively connects the augers to the gears c^7 , while permitting to the augers freedom for vertical movement through the said gears.

The gears c^7 on the auger-stems c^2 engage opposite sides of a common gear-wheel c^{10} , which is fixed to a vertical shaft c^{11} at the center of the truck. This shaft c^{11} extends upward through the yoke c^6 and a center-plate bearing c^{12} , supported by the tie-bars b^5 , and is provided on its upper end with a collar c^{13} , pinned fast to the said shaft. The said shaft c^{11} is also provided with a collar c^{14} , adjustably secured thereto and adapted to work on the upper surface of the yoke c^6 to divide the load on the said shaft c^{11} between the said two collars c^{13} and c^{14} and their respective bearings c^6 and c^{12} . The said shaft c^{11} carries, at its lower end, a beveled gear c^{15} , which engages with a beveled pinion or small gear c^{16} , loosely mounted on the main driving-shaft c^{17} . The said shaft c^{17} is mounted in suitable bearings c^{18} , fixed to the side bars b^2 , and is provided with a loose pulley c^{19} and a fast pulley c^{20} . The power is applied to the fixed or fast pulley c^{20} through a belt c^{21} from an engine or other available source of power. The loose pinion c^{16} and the loose pulley c^{19} are provided with half clutch-faces on their facing hubs, with either of which may be made to engage a two-faced clutch-sleeve c^{22} , mounted on the said shaft c^{17} and connected thereto in the usual way by means of an ordinary groove and feather c^{23} . The clutch-sleeve c^{22} is subject to the action of an ordinary shipper-lever c^{24} , pivoted to a rod c^{25} , which is secured to the transoms b^3 . The inward movement of the beveled pinions c^{16} is limited by a stop-collar c^{26} on the shaft c^{17} .

If the half-clutch c^{22} be thrown into engagement with the beveled pinion c^{16} , as shown in Fig. 4, then the shaft c^{11} will receive rotary motion from the driving-shaft, and the gearing $c^{10} c^7$ will turn the augers in common directions, as shown by the arrows on Fig. 3 of the drawings. If the clutch-sleeve c^{22} be thrown to its central position, as shown in Figs. 2 and 3, then the beveled pinion c^{16} and the pulley c^{19} will both remain idle; but if the sleeve c^{22} be thrown to the extreme right into engagement with the pulley c^{19} then the augers will not be rotated, but the pulley c^{19}

will receive rotary motion from the driving-shaft c^{17} .

The pulley c^{19} connects through belt c^{27} with pulley c^{28} on a counter-shaft c^{29} , mounted in suitable bearings c^{30} , fixed directly to the forward members of the frame-post b . The said counter-shaft c^{29} is provided at its right end with a pinion c^{31} , which engages with a gear c^{32} on a shaft c^{33} , which is mounted in suitable bearings c^{34} , also fixed to the posts b .

On the shaft c^{33} is loosely mounted a windlass-drum c^{35} , which has a half-clutch on its left-hand head. On the said shaft c^{33} is also mounted in the usual way, by feather and groove, a sliding half-clutch c^{36} , which is normally held in engagement with the half-clutch on the drum-head by a spring c^{37} , reacting between the same and a collar c^{38} on the said shaft c^{33} . The said half-clutch c^{36} is subject to the action of a pivoted shipper-lever c^{39} , pivoted to a bracket c^{40} , projecting from one of the posts b . The said shipper-lever c^{39} has attached thereto a pull-rope or flexible connection c^{41} , running over a guide-sheave c^{42} and extending downward to a point within reach of an operator standing on a foot-board c^{43} . The foot-board c^{43} is connected with the truck-platform by hinges c^{44} in such a way that when down the same may rest on the truck-wheels a and when up may be engaged by a retaining-button c^{45} .

The windlass-drum c^{35} is provided with cables c^{46} , which extend over suitable guide-sheaves c^{47} and multiplying-sheaves c^{48} to blocks and tackles c^{49} , the hooks of which are adapted to engage with suitable eyes c^{50} , provided in the upper ends of the auger-blade for raising the augers by a direct lift whenever so desired without any reverse rotary motion thereof.

The augers will be automatically clamped and held in whatever position they may be raised by the hub of a lever c^{51} , which is pivoted to a lug c^{52} of a bearing-bracket c^{53} , formed integral with the removable half of the yoke-bearing c^6 . The auger-stem sections c^2 work through the eyes or hubs of the clamping-levers c^{51} loosely whenever the axes of the hubs of said levers c^{51} are in line or coincident with the axes of the auger-stems, or, otherwise stated, whenever the said levers c^{51} are horizontal; but the said levers c^{51} are subject to the action of springs c^{54} , reacting between the same and the bearing-bracket c^{53} , which springs tend to throw the said levers c^{51} out of the horizontal position shown in Fig. 5 into a position which will bring the eyes or hubs of said levers at an angle to the auger-stems, as shown in Fig. 6. Whenever the said levers c^{51} are thus thrown into an angular position in respect to the auger-stems, the said stems will engage with the said eyes or hubs with a cramping action, increasing with the weight on the augers, and which is effective to clamp the augers to the said levers c^{51} until the said levers are released and thrown back to the horizontal position. For the pur-

pose of effecting this release the said levers c^{51} are shown as provided with a pull-rope c^{55} , which extends downward to a point within reach of the operator on the foot-board c^{48} .
 5 The outer end of the bearing-bracket c^{53} is turned up, so as to serve as a stop to limit the downward movement of the said levers c^{51} . In practice means would be provided for tying down the pull-rope c^{55} or for otherwise 10 locking the said levers c^{51} in their horizontal position, as required to avoid interference with the feed movement of the augers when at work in the boring action.
 All the parts of the excavator have now 15 been specified, and the action of the same is probably clear from the description given in connection with the specification of the parts. The general action may, however, be briefly summarized as follows:
 20 In Figs. 1 and 2 of the drawings the augers are represented as having been drawn up by the drum and held by the clamping-levers c^{51} at a point where just ready to enter the ground. Supposing the machine to be in proper position and the power applied from an engine or other source, the blocks and tackles c^{49} would be unhooked from the augers, the clamping-levers c^{51} would be fastened down in their horizontal position, so as to permit the augers 25 30 to drop and feed into the ground, and the clutch-sleeves c^{22} would be fastened in the position shown in Fig. 4, so as to render the motion from the main shaft c^{17} available on the augers. Under the rotary motion on the augers they will bury themselves in the ground and elevate the dirt to the surface as long as the rotary motion continues. After the augers have been lowered to the desired depth the clutch c^{22} is shifted to its intermediate or 35 40 45 idle position and the blocks and tackles c^{49} are hooked fast to the upper ends of the auger-blade. The clutch-sleeve c^{22} is then shifted to the extreme right, so as to engage with the pulley c^{19} and impart winding-up motion to the drum c^{35} . Under this action of the windlass or hoisting-drum the augers, together with their load of earth, may be raised above the level of the ground by a direct lift. Whenever the augers reach the desired elevation 50 55 60 it is only necessary to release the clamping-levers c^{51} , so as to render the same subject to the spring c^{54} , and thereby the said levers c^{51} will assume the position shown in Fig. 6 and become effective to hold the augers in whatever position they may happen to be. The purpose of having the drum c^{35} loose on its supporting-shaft c^{38} and adapted to be connected therewith through the clutch device shown is to permit the drum to be released from the shaft at will for unwinding the cables, as required to engage the blocks and tackles c^{49} with the augers when in their lowermost position or in any other position below the point to which they had been last 65 previously raised by the windlass. After the hole has been made by the two augers to the desired depth in the way above described the

machine will be moved forward one step or more, according to whether the machine is being used to make an open trench or openings spaced apart from each other, as the case may be. 70

With the machine above described excavation can be rapidly effected.

It will be understood, of course, that minor 75 details of the construction disclosed might be changed without departing from the spirit of my invention.

It should have been noted that the belt c^{27} is subject to an ordinary belt-tightener c^{56} , 80 supported by the right side bar b^2 of the main frame.

What I claim, and desire to secure by Letters Patent of the United States, is as follows:

1. In an excavator, the combination with a 85 portable frame, of the pair of upright augers mounted for vertical movement thereon, a pair of spur-gears rotatively connected to but free for sliding motion on the auger-stems, and a spur-gear between said auger-gears and engaging with both, substantially as described. 90

2. In an excavator, the combination with a 95 portable frame, of the pair of upright augers mounted for vertical movement thereon, the pair of gears rotatively connected to the auger-stems but free for sliding motion of the same, the central gear having its opposite sides engaged by said auger-gears, the vertical shaft supporting said central gear, and means for driving said shaft, substantially as described. 100

3. In an excavator, the combination with a portable support, of a pair of upright augers mounted for vertical movement on said support, gears on the auger-stems, rotatively connected thereto but free for sliding motion 105 thereon, fixed bearings forming guides for said auger-stems and seats for said auger-gears, and a yoke-bar having end bearings embracing the auger-stems and resting on the hubs of the auger-gears and forming part of 110 the support for the drive which operates said augers, substantially as described.

4. The combination with the portable support, of the upright augers mounted for vertical movement on said frame, the fixed bearings c^4 for the stems of said augers, the gears c^7 rotatively connected to but sliding on said auger-stems with their hubs resting on said bearings c^4 , the bearing-yoke c^6 with end bearings c^5 working on said auger-stems and resting on the hubs of said gears c^7 , the central vertical shaft c^{11} supported from the cap of the main frame and from said yoke c^6 , the central gear c^{10} on said shaft engaging said auger-gears c^7 and the drive c^{15} c^{16} c^{17} and c^{22} , 125 substantially as described.

5. In an excavator, the combination with the main frame or support of one or more upright augers mounted for vertical movement thereon, gears on the auger-stems rotatively connected thereto but free to permit sliding motion of the auger-stems therethrough, and pivoted clamping-levers with eyes or hubs through which the auger-stems work, for au-

automatically clamping and holding the augers wherever set in their vertical movement, substantially as described.

6. The combination with the supporting-frame, vertically-movable augers, windlass and connections therefrom for lifting the augers, of the driving connections for imparting rotary motion to said augers and windlass including as one element thereof a clutch for making the same rotate the augers or the

windlass at will, and a clutch controlling the connection of the windlass-drum with its supporting and driving shaft, for unwinding the drum at will, substantially as described.

In testimony whereof I affix my signature ¹⁵ in presence of two witnesses.

JOHN M. CARROLL.
